UNITED STATES PATENT OFFICE.

HENRY A. KENT, OF LONDON, ENGLAND.

SELF-LIGHTING GAS-BURNER.

SPECIFICATION forming part of Letters Patent No. 556,506, dated March 17, 1896.

Application filed October 14, 1895. Serial No. 565,658. (No model.)

To all whom it may concern:

Be it known that I, HENRY ANDREW KENT, engineer, a subject of the Queen of Great Britain and Ireland, residing at The Limes, 5 Brownlow Road, Bowes Park, London, in the county of Middlesex, England, have invented certain Improvements in or Connected with Gas-Burners of the kind known as Self-Lighting Burners, of which the following is a specification.

This invention has for its object to provide an efficient and durable means in connection with gas-burners in which the gas is lighted without the use of matches or the like. It is known that platinum-black, or platinum in a fine state of division, when subjected to the action of illuminating or heating gas and air will become heated to such a degree that by means of a platinum wire it will cause 15 the gas issuing from the burner to be ignited, but hitherto considerable difficulties have arisen in its practical application, the principal being that the platinum being subjected to the action of the flame of the main burner 20 has soon been converted into a carbide, and is then unfitted for its purpose. It has been proposed to overcome this difficulty by providing a by-pass for the gas to be first ignited and then to be diverted from the by-pass 25 to the main supply to be ignited, but this necessitates the provision of special taps and extra pipes or passages, and is therefore expensive and difficult to apply to ordinary gas-fittings, whereas a device according to this 30 invention can be readily applied to ordinary gas-fittings.

This invention consists in first causing a small supply of gas to pass in contact with the platinum or the igniting material used, 40 and to become ignited thereby, the heat of the flame so produced being caused to act upon a device which, under the influence of this heat, is caused to effect the closing of the supply of gas to the platinum and to 45 open the supply of gas to the main burner, the flame first kindled at the platinum after igniting the gas issuing from the main burner being extinguished, and the platinum thus 50 protected from the injurious effect of a continued subjection to the action of a flame. The platinum-black and platinum wire are

preferably inclosed in a tube or chamber to prevent injury or displacement of the same.

The device which is acted upon by the heat of the flame of the small jet first ignited may 55 consist of any arrangement which can be caused to alter its dimensions or position under the influence of heat sufficiently to open the supply of gas to the main burner and afterward close the supply of gas to the 60 small jet first ignited.

The accompanying drawings illustrate arrangements according to my invention.

Figure 1 is a vertical section, and Fig. 2 a plan, of the chamber C with the upper parts 65 removed. Figs. 3 and 4 are a front elevation and a vertical section of the arrangement applied to what is known as an "incandescent gas-burner," and Fig. 5 is a vertical section of the arrangement applied to an Argand 70 burner.

A is the main burner and B the igniting device.

C is a chamber into which the gas is admitted, it passing from this chamber to the 75 igniting device by the small perforation b, and to the main burner by the passage a.

D is a corrugated box or case which may contain air, gas, or liquid, the said box or case when it expands under the action of 80 heat, by acting, for instance, on the levers E and F or the like, closing the perforation b to the flame ignited by the platinum and opening the valve a², which admits the supply 85 of gas to the main burner through the passage a.

The corrugated box or case D may be contained in the chamber C, through which chamber the gas passes on its way from the gas-supply pipe G (controlled by the tap g) to the 90 platinum-igniter B and to the main burner A through the passage a and perforation b, respectively. The levers E and F are secured at one end to the inside of the chamber C, so that when they are acted upon by the expansion 95 of the corrugated box or case D the valve d, secured to one of them, closes the perforation b for gas to the igniter B, and after the other of them has opened the passage a for 100 gas to the main burner A, and thus the main supply of gas is ignited and the igniter-flame is extinguished, the valves being so operated

that the gas is admitted by the passage *a* before it is cut off from the perforation *b*.

When the supply of gas is turned off the apparatus cools and the parts return to the 5 positions ready to act to ignite the gas when it is again turned on.

H is a sheath which incloses the platinum and wire of the igniter to protect them from injury.

10 The arrangements shown in Figs. 3, 4, and 5 differ from that shown in Figs. 1 and 2 in the positions of the parts to adapt them for use with the particular burners shown, and the parts are marked with the same letters 15 as those used to indicate corresponding parts in Figs. 1 and 2.

In Figs. 3 and 4 the position of the igniter *B* and chamber *C* near the mantle *X* of the incandescent gas-burner necessitates the use 20 of the pipes *y* and *z*, as shown, to conduct the gas to and from the chamber *C*.

In Fig. 5 the chamber *C* is provided with a compartment at top communicating with the burner and separated from the main body of 25 the chamber by a diaphragm *c*, in which is the passage *a*, controlled by the valve for admission of gas to the main burner, the gas passing to the igniter by the pipe *b*² and box *b*³, from which the small orifice *b* opens.

30 The invention may be applied to gas-burners generally for illuminating or heating purposes.

Having now particularly described and ascertained the nature of this invention and in 35 what manner the same is to be performed, I declare that what I claim is—

1. In a self-lighting gas-burner, the combination with the main burner and the igniter, having passages leading thereto respectively,

a normally-closed valve in the passage to the 40 burner and a normally-open valve in the passage to the igniter, and means operated by the heating effect of the igniter for opening the valve to the main burner and for closing the valve to the igniter, substantially as de- 45 scribed.

2. In a gas-burner of the kind hereinbefore described, the combination with a main burner and an igniter, of a chamber through which the gas passes, said chamber being provided with passages leading to said main burner and igniter respectively, a valve-controller in said chamber actuated by the influence of heat, and valves operated by said controller when expanded by heat to first open 50 55 the passage to the main burner, and then close that to the igniter, as set forth.

3. The combination with a chamber connected with the gas supply, of a main burner connected with said chamber by a normally- 60 closed passage, an igniter arranged at the side of the main burner and connected with the chamber by a normally-open passage, said igniter being adapted to become ignited by contact of gas therewith, an expansible de- 65 vice in the chamber adapted to be operated by heat generated by the igniter, and valves operated by said device to first open the passage to the main burner and then close that to the igniter, substantially as described. 70

In testimony whereof I have signed my name to this specification in the presence of two subscribing witnesses.

H. A. KENT.
